UNITED STATES PATENT OFFICE

NORTON A. MEARS, OF CHICAGO, ILLINOIS, ASSIGNOR TO CHICAGO FORGING & MANUFACTURING CO., OF CHICAGO, ILLINOIS, A CORPORATION OF ILLINOIS

CLOSURE LATCH

Application filed April 17, 1930. Serial No. 444,888.

The invention relates to latches of the type employed in securing the movable cover of an automobile hood in closed position, and has especial reference to that type of latch which is enclosed within the hood with the operating handle projecting exteriorly of the hood.

A general object of my invention is to provide a latch of novel and advantageous construction such that it will at all times occupy a space inside the hood cover small enough to avoid interference with other parts within the hood.

In carrying out my invention I employ a latch construction including a resilient lever fulcrumed on one of the two members to be secured together and providing a latch arm adapted for swinging movement into and out of engagement with an abutment or keeper on the other one of said members.

With this in view, a further object of my invention is to provide a novel and effective means for operating the latch arm including an over center device operative to hold the lever under tension when in either its latched or inoperative positions.

The objects of the invention, thus set forth, together with other and ancillary advantages are attained in the embodiment of the invention illustrated in the accompanying drawing and hereinafter more particularly described, it being understood that various changes in the construction may be made by those skilled in the art without departing from the spirit and scope of the invention as expressed in the appended claims.

Figure 1 of the drawing is a vertical sectional view taken just inside the plane of the two parts to be connected, the latter being shown in fragmentary form.

Fig. 2 is a vertical sectional view taken approximately in the plane of line 2—2 of Fig. 1.

Fig. 3 is an under-side view with the hood parts shown in section.

While the invention is not limited to use in connection with automobile hoods, it is particularly applicable to such a use and will therefore be described in that environment.

Thus the latch is shown as applied to the inside of a hood of which 7 designates a section of the movable hood cover and 8 a fixed member on the automobile in part defining the opening closed by the hood, one edge of 55 the cover section being shown as slightly overlapping the fixed member. Mounted on the inside of the cover section is a relatively thin casing 9 having opposed side walls 10 and 10' spaced a short distance apart. Operable 60 within the casing is a lever generally designated 11. This lever is fulcrumed at one end on a pin 12, the opposite ends of which are supported in the two side walls of the casing at the upper end thereof and herein at the 65 corner remote from the edge of the cover. The free end portion of the lever 11 constitutes a latch arm 13 of a length such as to be swingable across the joint formed between the hood section and the fixed member into 70 engagement with an abutment 14 constituting a keeper on the fixed member of the automobile.

The lever 11 is preferably formed from a heavy wire or rod of suitable resilient material, and between its ends is constructed to provide a connection with the inner end of an operator generally designated 16.

The operator 16 comprises a shank 17 having at its outer end a handle 18 and at its inner end a double crank arm 19. The operator is rotatably supported in the opposed side walls of the casing, and the crank arm 19 is pivotally connected with the lever 11 intermediate the ends thereof, the rod forming 80 the lever being for this purpose formed with a single intermediate coil 20, which coil further increases the resiliency of the lever.

In order that the crank may be operative to swing the lever, the operator is rotatably and slidably supported at opposite sides of the crank in slots 21 formed in the opposed side plates of the casing 9, which slots, it will be observed, extend approximately radially from the pin 12 forming the fulcrum for the lever. Registering with the slots 21 an elongated opening 22 is formed in the hood cover section 7.

The arrangement is such that by imparting a combined rotative and bodily movement to 100

the shank of the operator, which slidably engages the guide slots 21, the lever is swung about its fulcrum to carry the latch arm 13 into and out of engagement with the keeper 5 abutment 14. At either extreme end of such movement, the end of the crank 19 occupies a position at the end of the slots 21 remote from the fulcrum pin 12 for the lever, and such ends of the slots are positioned so that 10 the crank arm engaging therewith occupies an over center position.

In order to utilize the resiliency of the lever, the over-center movement of the crank arm occurs after the latch arm 13 engages 15 with the abutment in the latching position of the device, and after the latch arm engages with a stationary part of the casing in the unlatched position of the device. Thus, it will be apparent that the lever arm may be held 20 under tension by the crank arm in either extreme position of the lever 11. This is important in the latching position because it insures that the movable parts of the hood or 25 other structure will be held firmly against movement, and it is important in the unlatched position of the device, since it enables the use of the handle 18 as a lifting device for the hood cover without danger of accidental operation of the lever into latching 30 position.

In order that the latch may be effective to restrain the hood cover against outward movement the lower surface of the keeper abutment 14 is inclined upwardly and inwardly as indicated clearly in Fig. 2 to form 35 a cam surface 23. Moreover the free end of the latch arm is guided for up and down movement by flanged guides 23^a on the casing. It will thus be apparent that by reason 40 of this shape of the keeper coupled with the resiliency of the latch arm when under tension and the guiding of the arm by the casing, the hood cover will be drawn and held firmly in position in overlapping relation to 45 the fixed member 8.

The keeper abutment 14 may be constructed economically from sheet metal. Thus it may comprise a base plate 24 having integral with 50 opposite side edges thereof arms 25 which may be bent at their free ends into abutting relation to form the inclined cam surface 23.

It will be seen that I have provided a latch of advantageous character, simple in construction and effective in operation, and furthermore of such compactness that it is capable of use in small or restricted spaces.

I claim as my invention:

1. A device for securing a movable closure member comprising, an abutment projecting 50 from means defining the opening closure of the member, a lever pivoted on the member and adapted to be swung into and out of engagement with said abutment, and a crank arm to swing said lever having one end journaled in said lever and the other end guided

in the lever supporting member for rotational and bodily sliding movement radially from the point of support of said lever.

2. A latch for automobile hood covers and the like, comprising, in combination, an abutment projecting from one of the two parts to be connected, a lever fulcrumed on the other part for rotation in a plane parallel thereto, and an over-center device for rotating said lever into engaging or retracted position relative to said abutment, said device comprising a crank having an arm pivotally connected at one end with the lever and guided at the other end in the parts supporting said lever for bodily sliding movement into over-center relation to the lever.

3. A latch for hood covers and the like, comprising, an abutment projecting from one of the two parts to be connected, a resilient lever fulcrumed on the other part for rotation in a plane parallel to the cover, means providing a slot disposed substantially radially of the lever fulcrum, and a crank journaled at one end in said lever and guided at the other end in said slot, said slot extending radially outward to permit of movement of the crank into perpendicular relation to said slot.

4. A securing latch for an automobile hood having a movable cover member overlapping a fixed member comprising, an abutment projecting from the fixed member, a casing mounted on the interior of the movable cover member, a resilient lever fulcrumed in said casing for movement in a plane parallel to the cover and having a latch arm projecting therefrom for engagement with said abutment, and an over-center device for rotating said lever comprising a U-shaped crank pivoted at one end to said lever, means for rotatably supporting the other end of the crank permitting bodily movement thereof in a direction extending substantially radially from the fulcrum of said lever and lying between the extreme positions of said lever, the elements of the latch being proportioned and positioned so that said arm engages said abutment before said crank reaches the neutral or equilibrium position of the device.

5. An automobile hood latch for securing a movable cover member in position, comprising, an abutment secured on the interior of a fixed member of the automobile, the lower edge of said abutment sloping inwardly, a casing mounted on the interior of the movable cover member, and a lever fulcrumed in said casing for rotation in a plane parallel with the hood cover and adapted to engage the sloping edge of said abutment, said casing having a narrow vertical slot guiding the lever and resisting the inward force created by the sloping surface of said abutment to hold the hood cover against movement perpendicular to the fixed member.

6. A latch for an automobile hood com-

- prising, in combination, an abutment on a fixed member of the automobile, a lever of resilient construction pivoted on the hood and swingable into engagement with said abutment, and an operator engaging said lever and rotatable about an axis to swing said lever, said axis being movable transversely to position said operator by distortion of said lever in holding relation thereto.
- 10 7. A latch for an automobile hood comprising, in combination, an abutment on a fixed member of the automobile, a lever fulcrumed on the hood and swingable into engagement with said abutment, and an operator with a crank arm having one end journaled in said lever and the other end rotatably supported in the hood member carrying said lever and guided in the member for movement transversely of its axis of rotation, said lever
- 15 engaging said abutment before reaching the limit of movement imparted by said operator and the limit of permissible transverse movement of said crank arm, said lever being yieldably constructed to permit said crank arm to
- 20 be moved beyond the position imparting maximum movement to said lever.
- 25 In testimony whereof, I have hereunto affixed my signature.
